UNITED STATES PATENT OFFICE.

JESSE A. CRANDALL, OF BROOKLYN, NEW YORK.

COMBINED WHEEL-CHAIR AND BABY-CARRIAGE.

SPECIFICATION forming part of Letters Patent No. 601,500, dated March 29, 1898.

Application filed August 6, 1897. Serial No. 647,314. (No model.)

To all whom it may concern:

Be it known that I, JESSE A. CRANDALL, a citizen of the United States, residing at Brooklyn, in the county of Kings and State of New York, have invented certain new and useful Improvements in a Combined Baby-Carriage and Wheel-Chair, of which the following is a specification, reference being had therein to the accompanying drawings, in which—

5 Figure 1 is a side elevation of my improved vehicle arranged for use as a baby-carriage, and Fig. 2 a perspective view arranged as a wheel-chair.

10 This invention has reference to that class of perambulators covered by my former patent, No. 586,760, dated July 20, 1897, in which the body of the baby-carriage was divided transversely about midway its length, the front section being detachable to convert the

15 baby-carriage into a wheel-chair and the rear section being permanently supported on a pair of main transporting-wheels and provided with handles at its rear end and at its front end with a depending support and step-piece,

20 the support preferably carrying a pair of supplemental small wheels. In said patent the front section is shown entirely detachable and the step-piece was attached directly to the front depending support. My present im-

25 provements consist, essentially, in hinging the front section to the permanent rear section in such a manner that when the baby-carriage is to be converted into a wheel-chair said front section may be dropped down and

30 permitted to rest upon the depending support carrying the auxiliary wheels, the curvature of the lower side of the front section being preferably made to conform to the curvature of said depending support in order to firmly

35 support the front section in its let-down position and add symmetry to the appearance of the wheel-chair. A portion of the bottom of the front section is hinged or made otherwise removable, so that it may be extended

40 or swung outward when the front section is let down to afford a suitable step or foot-rest, as more fully hereinafter set forth.

45 Referring to the drawings by letters, *a* designates the rear permanent section of the body

50 of the baby-carriage, this section being suitably supported upon the main or large wheels

b and being provided with the usual upward-projecting handles *c* at its rear and with the depending forward-projecting support *d* at its front end, this support carrying the small auxiliary wheel *e*. The front section *f* of the body of the baby-carriage is hinged at its lower edge to the front lower edge of the rear section and is held in place by a pair of links or arms *g*, which are pivoted at their rear ends 55 to the respective sides of the rear section and have their front ends detachably connected to the adjacent sides of the rear section, thereby supporting the latter in alinement with the front section and giving the body of the 60 carriage the appearance of the ordinary baby-carriage. A transverse portion *h* of the bottom of the front section is pivoted at its forward end, as at *h'*, and its front edge rests upon a flange or stop *h''*. 70

When it is desired to convert the baby-carriage into a wheel-chair, it is simply necessary to detach the links *g* from the front section and let the latter down upon the depending support and then unfold or open out 75 the foot-rest *h*, which latter in its opened-out position rests upon suitable stops *h''*, projecting inward from the sides of the front section, as shown in Fig. 2.

Having thus fully described my invention, 80 what I claim, and desire to secure by Letters Patent, is—

1. A combined baby-carriage and wheel-chair, comprising a pair of supporting-wheels, a carriage-body supported thereon and being 85 divided transversely into two sections, the front section being movably connected to the rear section and adapted to drop down to convert the carriage into a wheel-chair, a transverse section of the bottom of the front section being movable, and means for supporting said transverse movable section between the sides of the front section when the same is let down, thereby converting said transverse section into a foot-rest. 90

2. In a combined baby-carriage and wheel-chair, the combination of transporting-wheels, a carriage-body divided transversely and the front section being movably connected to the rear section, to adapt the front section to 100 be lowered, and a step or foot rest hinged to the front section and adapted to be swung

out and afford a foot-rest when the front section is let down, as and for the purposes set forth.

3. A combined baby-carriage and wheel-chair, comprising supporting-wheels, a carriage-body divided transversely, the front section being adapted to be let down to convert the vehicle into a wheel-chair, a depending support attached to the rear section and adapted to afford a support for the front sec-

tion when the same is let down, and a foot-rest supported between the sides of the front section, substantially as described.

In testimony whereof I affix my signature in presence of two witnesses.

JESSE A. CRANDALL.
